(57) CLAIM

The ornamental design for a lighter with a clip, as shown and described.

DESCRIPTION

FIG. 1 is a perspective view of the lighter with a clip showing an embodiment of my new and ornamental design; FIG. 2 is a left side view thereof;

FIG. 3 is a right side view thereof;

FIG. 4 is a rear side view thereof;

FIG. 5 is a front side view thereof;

FIG. 6 is a top side view thereof; and,

FIG. 7 is a bottom view thereof.

The portions indicated in broken lines are for illustrative purposes only and form no part of the claimed design.
